UNITED STATES PATENT OFFICE.

HORACE G. FISHERING, OF XENIA, OHIO.

FUNNEL.

SPECIFICATION forming part of Letters Patent No. 267,861, dated November 21, 1882.

Application filed September 1, 1882. (No model.)

To all whom it may concern:

Be it known that I, HORACE G. FISHERING, a citizen of the United States, residing at Xenia, in the county of Greene and State of Ohio, have invented certain new and useful Improvements in Funnels, of which the following is a specification, reference being had therein to the accompanying drawings.

My invention relates to funnels; and it consists in the construction and arrangement of its several parts, as will be hereinafter fully set forth, and pointed out in the claims.

In the drawings, Figure 1 is a vertical longitudinal section; Fig. 2, a cross-section upon the line $x x$, Fig. 1.

A is the funnel. It is provided with measuring-groovings a , grooved around its circumference, and with a suitably arranged valve, a' , which closes the spout a^2 , as shown. Hinged to the exterior of the funnel, preferably upon the same line with the lower measuring-groove shown, are supports B. The ends of these supports extend somewhat below the discharge-spout a^2 , so that the funnel is held from contact with the surface upon which it rests. This function of the supports is plainly shown in Fig. 1. Secured at an equal height upon each support are keepers b. One of them is supplied with a set-screw, b' , upon its vertical side, as shown. Extended around the supports and through the keepers is the band b^2 , both ends of which pass within the keeper having the set-screw, so that when said screw is turned down upon the band the supports will

be prevented from turning upon their hinges. 35 When the set-screw is loosened the ends of the band slip easily past each other and permit any desired adjustment of the supports. By this arrangement, when the funnel is placed in the spout of a jug or keg the supports can be adjusted against its sides and the set-screw turned down upon the band. The supports then serve as braces to prevent the funnel from tipping over by reason of the weight of the liquid. 40 45

What I claim is—

1. The combination of the funnel, provided with suitable measuring-groovings, with the hinged valve, the hinged supports, and means whereby the supports may be adjusted to the 50 sides of a jug or vessel, all arranged to operate substantially as shown and described.

2. A funnel provided with hinged supports and having a band secured around said supports, whereby they can be adjusted at any 55 angle to the funnel, as set forth.

3. The combination, with a funnel having supports hinged thereto, with keepers placed upon them, of the band passed through said keepers, and means to hold the band, as set 60 forth.

In testimony whereof I affix my signature in presence of two witnesses.

HORACE G. FISHERING.
